SILVERWARE BASKET

Louis Maslow, Huntsville Road, Dallas, Pa.

Original design application June 3, 1964, Ser. No. 80,269.
Divided and this application Apr. 7, 1965, Ser. No.
85,331

Term of patent 14 years

(Cl. D44—29)

FIG. 1

FIG. 2

H-5

H-5

FIG. 3

FIG. 4

FIG. 5

FIG. 6

FIGURE 1 is a side elevational view of a silverware basket showing my new design;

This is a division of my co-pending application Serial No. D. 80,269, filed June 3, 1964.

I claim:

The ornamental design for a silverware basket substantially as shown and described.
